[57] CLAIM

The ornamental design for a cart for storing dishes or the like, as shown.

DESCRIPTION

FIG. 1 is a perspective view of a cart for storing dishes or the like, showing our new design;

FIG. 2 is a side elevational view thereof, the opposite side elevational view being a mirror image of that shown;

FIG. 3 is the top plan view thereof; and

FIG. 4 is a bottom plan view thereof.
